UNITED STATES PATENT OFFICE.

ALBERT H. STEBBINS, OF LOS ANGELES, CALIFORNIA.

TABLE CONCENTRATOR.

Application filed May 5, 1923. Serial No. 636,809.

To all whom it may concern:

Be it known that I, ALBERT H. STEBBINS, a citizen of the United States, residing at Los Angeles, in the county of Los Angeles 5 and State of California, have invented an Improvement in Table Concentrators, of which the following description, in connection with the accompanying drawings, is a specification, like characters on the drawings representing like parts.

This invention relates to concentrators of the table type for the separation of ores and other materials in accordance with their differences in specific gravity.

15 Most metals or values have a higher specific gravity than the accompanying impurities and are usually distributed throughout a relatively large amount of impurities or foreign matter, so that it is necessary to 20 treat a large amount of material as compared with the values obtained therefrom.

The present invention relates to the type 25 of table concentrator which employs a transversely inclined deck surface having riffles extending in an inclined direction over the deck surface and arranged to direct the heavier materials or values toward the upper side of the deck while the lighter materials or tailings pass over the top of the 30 riffles toward the lower side of the deck.

In concentrators of this type movement 35 may be imparted to the deck to advance the materials being treated over the surface of the same, and the movement imparted to the deck should be such that it will advance the materials progressively without disturbing the strata into which the materials are being separated. One important feature of the present invention, therefore, resides in 40 novel means for imparting a back and forth movement to the deck for advancing the materials progressively along the deck surface.

Separation of the materials into different 45 strata or layers is promoted by passing air upwardly through the deck surface and the materials thereupon, and another feature of the invention resides in a novel disposition of the air delivering apertures 50 formed in the deck surface.

Other features of the invention reside in 55 improvements in the construction of the riffles, and in the deck surface for promoting bunching of the materials traveling along the riffles.

Still other features of the invention re-

side in novel means for adjusting the deck to different inclinations and for clamping the same in the desired position of adjustment, and in novel means for supporting the deck for back and forth movement.

Other features of the invention and novel combination of parts in addition to the above will be hereinafter described in connection with the accompanying drawings which illustrate a good practical form thereof.

In the drawings:

Fig. 1 is a side elevation of a table concentrator constructed in accordance with the present invention, the deck cover being removed.

Fig. 2 is an enlarged perspective view of a portion of the deck surface shown in Fig. 1.

Fig. 3, is a top plan view of the deck supporting and operating means, the deck being removed.

Fig. 4 is a side view of the deck and deck supporting frame, viewing the side opposite to that shown in Fig. 1.

Fig. 5 is an enlarged sectional view taken on the line 5—5 of Fig. 1.

Fig. 6 is an enlarged vertical sectional view through clamping means to be described.

Fig. 7 is a sectional view taken on line 7—7 of Fig. 6.

Fig. 8 is a plan view of the deck surface.

Fig. 9 is a side elevation of a portion of a table concentrator having modified deck operating means.

Fig. 10 is a side view of still another modification of the deck operating means; and

Fig. 11 is a longitudinal sectional view 95 through one of the surface channels of which the deck surface is formed.

The table concentrator shown consists of a fixed frame 10 upon which the movable frame 11 is mounted, and upon the frame 11 is mounted a deck 12 having provisions for adjustment to different transverse inclinations upon the frame 11.

The fixed frame 10 may be of rectangular configuration and is formed of longitudinally extending, side-rails 13, 14 and 15 secured in spaced relation by uprights 16 and laterally extending beams 17.

The movable frame 11 is rectangular in plan view and consists of the longitudinally extending side bars 18 rigidly connected by the transversely extending beams 19, and

the frame 11 has an inclined bar 20 secured thereto and upon which supporting clamps 21 for the deck 12 are mounted. The side bars 18 may be formed of U-shaped angle 5 irons, as best shown in Fig. 5, to provide the lower laterally extending flanges 22 and the upper laterally extending flanges 23, and angle irons 24 L-shaped in cross section may be rigidly secured to the flanges 23. The 10 deck 12 is secured to the movable frame 11 by hinges 25, and these hinges are shown as secured to the under face of the deck and to longitudinally extending strips 26 secured to the upstanding portion of the 15 L-shaped angle irons 24.

It is desirable that means be provided for adjusting the deck 12 to different transverse inclinations to vary the flow of the materials laterally over the riffles toward the 20 lower side of the deck, and that clamping mechanism be provided for rigidly securing the deck in the desired position of angular adjustment. In the construction 25 shown an adjusting screw 27 and cooperating hand wheel 28 serve to adjust the deck to the desired transverse inclination upon the frame 11. The upper end of the screw 27 is seated in a socket formed in a block 29 secured to the under face of the deck 12 30 and the screw 27 extends downwardly into threaded engagement with the hand wheel 28 rotatably mounted on a transversely extending beam 19 of the frame 11. As the hand wheel 28 is rotated in one direction the 35 deck will be rocked upwardly about the hinges 25, and when rotated in the opposite direction the deck will be rocked downwardly.

The deck 12 as will be apparent from Figs. 40 1 and 8, tapers toward its material discharge end and the inclined bar 20 secured to the frame 11 is inclined at an angle corresponding to the taper of the deck 12, and after the deck has been adjusted to the desired 45 transverse inclination it is clamped in this position of adjustment by brackets 21 extending upwardly from the bar 20 and cooperating brackets 30 extending downwardly from the under face of the deck 12. The 50 brackets 21 and 30 as best shown in Figs. 6 and 7 are provided with elongated bolt-receiving slots 31 and 32 adapted to receive the clamping bolt 33. A flexible bracket 34 preferably is secured to the bar 20 in spaced 55 relation to the bracket 21 to provide a space therebetween for the downwardly extending portion of the bracket 30, and the bolt 33 serves to clamp the bracket 30 between the brackets 21 and 34. The space between 60 the spaced brackets 21 and 34 serves to receive an abutment block 35 upon which the lower end of the bracket 30 may rest to assist the clamping bolt in supporting the weight of the deck.

65 As stated the deck supporting frame 11

is mounted upon the fixed frame 10 for back and forth movement thereupon, and the mounting is preferably such that a slight up-throw movement is imparted to the materials upon the deck as the movement of the deck is arrested in the material advancing direction. In the present case the under-throw type of mounting is employed, and crank rocker shafts 36 extending transversely across the fixed frame 10 are journaled between their ends in bearing brackets 37. At each end of the shafts 36 are provided downwardly extending crank arms 38 having stub shafts 39 mounted in journal boxes 40 secured between the flanges 22 and 23 of the side bars 18 of the deck supporting frame 11. The arrangement is such that the deck frame 11 is supported by the shafts 36 at points below the fixed bearings in which these shafts rotate and as a result, 80 the deck will rise and fall slightly as the crank shafts 36 rock back and forth.

A back and forth movement is imparted to the deck to promote travel of the materials being treated along the same, and this movement should be such that it will advance the materials along the deck without disturbing the stratification of the same that is being effected. The materials preferably are advanced along the deck by suddenly 95 arresting the movement of the deck in one direction so that the momentum imparted to the materials will cause them to slide along the deck slightly after the movement of the latter has been arrested. Novel 100 means for imparting the desired movement to the deck will now be described.

The deck carrying frame 11 is supported by the rock shafts 36 for back and forth movement and this frame is normally urged in the right hand direction (Fig. 1) by one or more springs 41 each having one end abutting against a transversely extending beam 42 of the frame 11, and the other end resting against an adjusting screw 43 supported by a bracket 44 mounted upon the frame 10. In the present case movement of the deck supporting frame 11 in the opposite direction is effected by one or more cables, chains or belts 45 (Fig. 1) having one end secured to the frame 11 at 46 and the other end anchored to the fixed frame 10 by an adjustable bolt 47. Means is provided for tightening the cable 45 to move the deck frame to the left against the tension of the springs 41, and for reducing the tension of the cable to permit the frame to be moved in the opposite direction by the springs 41.

In the embodiment of the invention shown in Fig. 1, this is accomplished by providing a drum 48 with one or more cable engaging pulleys 49, and the drum 48 has a central bore adapted to receive rotatably an eccentric 50 upon the shaft 51. The shaft 51 is journaled in bearings 52 mounted upon the 130

side rails 14 of the fixed frame and the shaft is rotated by the driving wheel 53. The arrangement is such that the cables 45 pass around a portion of the pulleys 49, and as 5 the shaft 51 is rotated the drum and pulleys are moved in an orbital path by the eccentric 50, this exerts a pull upon the cable as the drum is forced to the left by the eccentric, and slacks off the cable as the drum is moved 10 to the right, it being understood that the drum does not rotate with the eccentric but is moved bodily thereby in an orbital path.

It will be noted that the movement of the 15 pulleys 49 which tighten and slack the cables 45 is primarily the movement of the pulleys in a horizontal direction, while the tension of the cable is effected only slightly by the movement of the pulleys in the vertical direction. The operating eccentric 50 may be 20 regarded as having a "dead center" at each end of its stroke where it uses up a period of time during which it neither pulls or releases the cable appreciably. This occurs when 25 the eccentric is substantially on the line A—C of Fig. 1 with the eccentric extending toward A or toward C. At C the deck is at the end of its back stroke (or pull), and at A the cable is slackened off and the deck is at the end of its forward stroke.

30 As the eccentric turns from A to C in the clockwise direction it stretches the cable taut and pulls the deck back against the tension of the springs, and as the eccentric passes the dead center at C the slowest movement 35 is imparted to the deck and the direction of movement of the deck is changed without shifting the materials upon the deck surface. As the eccentric continues its movement in a clockwise direction from C toward A the cable is slackened off and the 40 springs push the deck forward to take up the slack of the cable, and the angular disposition of the crank rocker shafts 36 at the beginning of the forward movement of the 45 deck assist the springs 41 in moving the deck to the right.

When the eccentric reaches the position A the slack is nearly all taken up, but there still remains the final tightening up of the 50 slack cable which requires a very short period of time, but sufficient for the eccentric to pass slightly below the line A—C so that the pulley grips the cable suddenly and begins the next backward pull. This 55 quick gripping of the cable with its immediate backward pull is the important effect, as it arrests suddenly the movement imparted to the deck by the springs 41 and causes the momentum imparted to the materials to 60 slide them along the deck surface, at the same time a slight up-throw movement may be imparted to the deck by the crank arms 38 supporting the same, as will be apparent from Fig. 1 wherein the parts are shown as 65 at the end of the material advancing stroke.

The rotation of the eccentric from its uppermost position toward A may assist somewhat in increasing the speed at which the cable is slackened off and this promotes a quickened forward stroke. Also the pull 70 against the driving means for the eccentric shaft 51 as the eccentric rotates from A toward C helps to slow down the turn at C. Further the weight of the drum on the rising eccentric as the latter rotating upwardly 75 from C helps to slow down the turn at C, and the first half of the movement from C toward A is likewise slowed down slightly, while the movement of the eccentric from its uppermost position toward A and about 80 the dead center at A is speeded up somewhat by the weight of the drum.

The quick gripping of the cable and the increasing speed in the drum moving downwardly in rotating toward A are the important effects, but the two other results contribute in producing the desired result, and the combination of all these influences give an accelerated forward movement to the right with quick turn at the forward end of 90 the stroke, and a slowing backward movement to the left with a slower turn at the back end of the stroke. This construction it is found imparts a very satisfactory movement to the deck, and is an important improvement over the deck operating means heretofore employed. The arresting of the movement of the deck in the material advancing direction may be assisted by providing the deck supporting frame 11 with a bumper 95 100 54 that may strike against a bracket 55 mounted upon the fixed frame 10, but this is not an essential feature, as the cable operating means above described is adapted to arrest the movement of the deck suddenly 105 enough to produce the desired result.

The deck 12 may be variously constructed and is shown as comprising a relatively long hollow casing, that tapers toward the material discharge end, and is provided with a 110 deck surface 56 supported in spaced relation to the bottom of the casing. The chamber below the deck surface may be divided into different compartments by longitudinally extending partitions 57, and air may be delivered to the chamber below the deck surface from a fan 58 connected to the wide end of the deck chamber by a hood 59. The fan 58 may be driven from the pulley 60 upon the shaft 51 by a belt 61.

The present invention contemplates different improvements in the construction of the deck surface 56 which will now be described.

The deck surface 56 is provided with inclined riffles 62 which extend from the lower side of the deck to the concentrate wall 63 extending along the upper side of the deck, and the materials to be treated are delivered to the deck surface at one end thereof from 125 130

the hopper 64. The deck surface is provided with apertures 65 for the passage of air upwardly therethrough and through the materials upon the deck surface to remove 5 the dust and to promote stratification of the materials. The deck surface preferably is formed of the individual surface channels 66 placed side by side and which are U-shaped in cross section and have upwardly extending sides that form the riffles 62.

The air passing upwardly through the deck surface, and the movement imparted to the deck cause the materials to spread out rapidly over the deck surface and to travel 15 lengthwise of the same, and the heavier materials settle quickly and crowd upwardly the lighter materials. As a result the heavier materials will travel along the riffles and will be guided thereby toward the 20 concentrate wall, while the lighter materials will flow over the top of the riffles laterally toward the lower side of the deck where they escape over the discharge board 67.

25 Separation of the materials in accordance with their differences in specific gravity is promoted by causing the lighter materials to bunch or pile up slightly along the riffles and then flow laterally over the riffles 30 toward the tailing discharge side of the deck. In the present case this bunching or piling up of the materials is promoted by providing the riffles at intervals with sections 68 that are slightly higher than the 35 remaining portions of the riffles. These raised sections may be provided over the deck surface at intervals in a more or less staggered arrangement to bunch the flow of the materials whenever it may be desired.

40 As a result the materials traveling along a riffle behind a raised section 68 will not flow laterally over the riffle until they pass out from behind the section 68 whereupon they will flood over the riffle, in this manner a 45 series of accumulations of the light materials are formed behind the sections at intervals over the deck surface and they flood over the riffles as they escape from behind the sections. The sections 68 need be only 50 slightly higher than the remaining portion of the riffles, and may be several inches long to cause sufficient materials to accumulate behind the same to flood over one or more riffles upon escaping therefrom.

55 In addition to providing the sections 68 back of which the lighter materials may accumulate, it may be desirable to promote bunching of the materials traveling along the riffles to cause the lighter materials to 60 flow over the riffles as they approach the concentrate wall. In the present case this is accomplished by increasing the slope of the deck surface adjacent the concentrate wall as at 69, Fig. 5. From this view it 65 will be seen that the portion of the deck

surface extending along the concentrate wall 70 63 is bent upwardly slightly so that the materials traveling along the riffles toward the concentrate wall will pile up upon reaching this wall thereby to increase the cross flow 75 of the lighter materials.

Another feature of the present invention resides in the disposition of the apertures 65 within the deck surface. The stratification of the materials is an important part 80 of the separating operation, and this is produced by air passing upwardly through the materials upon the deck surface, and also by the movement imparted to the deck.

It is found that the fine particles of the 85 heavier materials or values are often carried up by the air passing upwardly through the deck surface. This is not desired as these fine values may be carried off with the lighter materials or tailings. To prevent 90 this the deck surfaces may be provided with portions where the perforations 65 are omitted, and the deck surface may be provided with other portions where the perforations 95 are opened very slightly. In Fig. 8 the deck is shown as having the perforations omitted along the lower side of the deck and from a portion of the delivery end of the deck, and the portions or patches where the perforations indicated as lying within the dotted enclosures 100

105 Passing the materials being treated over a dead air space formed by omitting the perforations, or other portions of the deck where the air currents are reduced, gives the fine values a chance to sift back down to the deck surface under the influence of the deck movement, and as the fine values are heavier they will settle more rapidly than the 110 lighter particles and prevent the latter from reaching the lower strata. The preferred position of the portions X of slight air currents is near the ends of the raised portions 115 68 of the riffles; that is near the points 70, see Fig. 11, which serve to direct the air as it passes through the apertures. The amount of air passing upwardly through the portion X of the deck surface may be 120 reduced as desired by closing the lips adjacent the apertures 65 as at 70^a, Fig. 11.

125 In Fig. 9 is shown a somewhat different application of cable means for imparting movement to the deck supporting frame 11. In this view an operating arm 71 is pivoted at its lower end to a bracket 72 and the upper end of the arm 71 is operatively secured to the deck frame 11. The connection between the arm and deck frame consists of a link 73 fastened to the frame 11 by a bolt 130

74, and the link is adjustably secured to the arm by a bolt 75 having adjusting nuts engaging the opposite faces of this arm. The operating cable 76 has one end secured to the 5 operating arm 71 by a bolt 77 and the other end of the cable is anchored to the fixed frame by an adjustable bolt 78. The cable 76 passes around an ordinary pulley 79 mounted on a shaft 80 supported by 10 brackets 81. The cable then passes around the pulley 82 mounted on the eccentric shaft 83 similar to the eccentric shaft 50 above described, and the shaft 83, is rotated by a pulley or other means not shown. The 15 cable then passes downwardly about an idle roller 84 and then to the bolt 78. The construction is such that as the eccentric shaft 83 is rotated it will tension and slack off the cable similar to the pulleys 49 above described, and as the cable is pulled taut it will rock the arm 71 to the left and pull the deck frame 11 in the same direction against the tension of the spring 41. As the pulley 82 is moved away from the cable 20 by its eccentric the cable will be slackened off and the deck frame 11 will move to the right under the tension of the spring 41, and as the deck approaches the end of its stroke in this direction it may be suddenly 25 arrested by the arm 71 striking against an abutment bracket 85. Resilient material 86 may be provided upon the arm and bracket respectively at the point of contact, and the position of the deck when the bump occurs 30 may be varied by adjusting the nuts upon the bolt 75.

It may be desirable to provide means for taking up the slack in the cable 76 as the 40 tension of the same is reduced by the rotating eccentric, and in the construction shown in Fig. 9 a coiled spring 87 is provided for exerting a pull in a lateral direction upon the cable 76. The spring 87 has one end secured to the cable at 88 and the 45 other end of the spring is adjustably secured to a bracket 89. The extent to which the cable 76 will be deflected laterally by the spring 87 may be limited by a strap 90 secured to the cable at 88 and extending 50 from the cable in a direction opposite to the spring 87, and the opposite end of this strap may be adjustably secured to a bracket 91. The strength of the spring 87 should be much less than the strength of the spring or 55 springs 41 that move the deck in one direction.

Still a different arrangement of the deck operating cable is shown in Fig. 10 wherein the cable does not pass around the pulley 60 or sheave 92 upon the cam shaft 93 but merely rests upon the upper face of this pulley. As a result of this construction the lower run of the cable 94 passing from the lower side of the pulley 95 to the stop 96 will be deflected upwardly as the cam shaft

93 rotates, and this will tighten the cable to pull the deck frame 11 to the left. In this modification a different form of cable tensioning means from that shown in Fig. 9 is provided. The tensioning means of 70 Fig. 10 consists of a spring 97 that acts upon the wheel 95 yieldingly to rotate the same in a contra-clockwise direction to take up the slack between the portion of the cable extending from the wheel to the deck. 75

What is claimed is:

1. A concentrator table comprising, in combination, a deck having means for supporting the same, a deck surface having riffles extending over the same and apertures between the riffles for the passage of air upwardly through the deck surface, and the deck surface having sections between the riffles where the apertures are practically closed to provide dead air spaces at said sections and which are surrounded by sections having apertures of substantial opening. 80

2. A concentrator table comprising, in combination, a deck having means for supporting the same, a deck surface having riffles extending over the same and having apertures between the riffles for the passage of air upwardly through the deck surface, lips extending upwardly in an inclined direction from the apertures to direct the air 90 passing through the apertures, and the deck surface having sections between the riffles where the apertures are practically closed to provide dead air spaces at said sections and which are surrounded by sections having apertures of substantial opening. 95

3. A concentrator table comprising, in combination, a deck having means for supporting the same at a transverse inclination, a deck surface, riffles extending across the 105 surface for directing the heavier materials along the riffles while the lighter materials pass laterally over the top of the riffles, upstanding portions upon the riffles at intervals over the deck surface and forming sections of increased height against which the materials may accumulate and then flood over the riffles as they pass from behind the raised sections, and the deck surface having apertures formed therein between the 110 riffles for the passage of air upwardly therethrough and having areas where the apertures are practically closed to provide dead air spaces surrounded by areas having apertures of substantial openings, and the 115 dead air spaces being located to promote re-stratification of the materials as they escape from behind the raised sections. 120

4. A dry concentrator table comprising, in combination, a deck having means for 125 supporting it at a transverse inclination, a deck surface having apertures therein for the passage of air upwardly therethrough and having a concentrate wall at its upper side, riffles extending in an inclined direc- 130

tion over the deck surface toward the concentrate wall, and a narrow portion of the deck surface extending along the upper side of the deck and over which the riffles extend 5 being bent upwardly slightly at an increased angle to increase the slope of the deck surface adjacent the upper side of the deck to increase the piling up of the material between the riffles as they approach the concentrate wall.

5. A deck for a dry concentrator table comprising, in combination, a deck surface having apertures therein for the passage of air upwardly therethrough and having a 15 concentrate wall extending along one side, riffles extending in an inclined direction over the deck surface toward the concentrate wall, and a narrow portion of the deck surface extending along the side of the deck 20 adjacent the concentrate wall and over which the riffles extend being inclined upwardly slightly relative to the rest of the deck surface to produce an up-slope that increases the piling up of the materials between the riffles as they approach the concentrate wall.

6. A concentrator table comprising, in combination, a deck having means for supporting it at a transverse inclination, a deck 30 surface, riffles extending across the surface for directing the heavier materials along the riffles while the lighter materials flow laterally over the riffles, raised portions extending upwardly from the riffles at intervals over the deck surface and forming sections of increased height against which the materials may accumulate and then flood over the riffles as they pass from behind the sections, and the deck surface having apertures formed therein between the riffles for 35 the passage of air upwardly therethrough and having areas between the riffles where the apertures are practically closed to provide dead air spaces located relative to the 40 points where the materials escape from behind the sections to give the materials an opportunity to re-stratify at said points.

7. In a concentrator table, in combination, a deck supporting frame, a deck mounted 45 thereupon for adjustment to different transverse inclinations, hinge means between the frame and deck for supporting one side of the deck, and clamping means for rigidly securing the opposite side of the deck to the 50 frame in different positions of angular adjustment, including brackets secured to the deck and frame respectively for overlapping engagement with each other, a third bracket mounted in spaced relation to one of said 55 brackets to receive the projecting portion of the remaining bracket between them in different positions of adjustment, means for

clamping the spaced brackets rigidly against the opposite faces of the intermediate bracket, and the spaced brackets being 65 adapted to receive in the space between them a block forming an abutment for the inner end of the intermediate bracket.

8. In a concentrator table, in combination, a deck supporting frame, a deck mounted 70 thereupon for adjustment to different transverse inclinations, hinge means between the frame and deck for supporting one side of the deck, and clamping means for rigidly securing the opposite side of the deck to 75 the frame in different positions of angular adjustment, including brackets secured to the deck and frame respectively for overlapping engagement with each other, a third bracket mounted in spaced relation to one 80 of said brackets to receive the projecting portion of the remaining bracket between them in different positions of adjustment, and means for clamping the spaced brackets rigidly against the opposite faces of the 85 intermediate bracket.

9. A concentrator table comprising, in combination a deck supporting frame having a deck thereupon, a fixed frame provided with a bearing for a shaft, a shaft 90 journaled in said bearing and having downwardly extending crank arms at its opposite ends, and bearings secured rigidly to the deck frame and having the lower ends of the crank arms journaled in the bearing 95 movably to support the deck frame suspended from the fixed frame by the downwardly extending crank arms.

10. A concentrator table comprising, in combination, a deck supporting frame having a deck thereupon, a fixed frame provided with bearings for receiving shafts extending transversely of the frame, shafts journaled in said bearings and having downwardly extending crank arms at their opposite ends, and bearings secured rigidly to the deck frame and having the lower ends of the crank arms journaled in the bearings movably to support the deck frame suspended from the fixed frame by the downwardly 100 extending crank arms.

11. A concentrator table comprising, in combination, a deck having means for supporting the same, a deck surface having riffles extending over the same and apertures 115 between the riffles for the passage of air upwardly through the deck surface, and the deck surface having sections distributed over the same and having the openings of the apertures substantially reduced within said 120 sections.

In testimony whereof, I have signed my name to this specification.

ALBERT H. STEBBINS.
